(57) **CLAIM**

The ornamental design for an emergency information card, as shown and described.

DESCRIPTION

FIG. 1 is a top front perspective view of the emergency information card;

FIG. 2 is a front elevation view thereof;

FIG. 3 is a rear elevation view thereof;

FIG. 4 is a left elevation view thereof;

FIG. 5 is a right elevation view thereof;

FIG. 6 is a top elevation view thereof; and,

FIG. 7 is a bottom elevation view thereof.

The broken lines shown in the drawings illustrate portions of the emergency information card that form no part of the claimed design.
